UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

CAR-TRUCK SIDE FRAME.

1,173,714.

Specification of Letters Patent. Patented Feb. 29, 1916.

Application filed July 6, 1915. Serial No. 38,248.

To all whom it may concern:

Be it known that I, WILLIAM D. FORSYTH, a citizen of the United States, and a resident of the city of Youngstown, in the county of Mahoning and State of Ohio, have invented a new and useful Improvement in Car-Truck Side Frames, of which the following is a specification.

The invention relates to steel side frames for wheel trucks of freight cars, and consists of a rigid frame or truss connecting the journal boxes and which is composed of forged or pressed steel members which are riveted together.

15 The object of the invention is a side frame or similar part which is sufficiently durable to withstand hard service, and which is designed and constructed as to give a maximum capacity in proportion to its weight 20 for supporting vertical loads and side thrusts without undue deflection.

Further objects of the invention will appear in connection with the following description of the side frames illustrated in 25 the accompanying drawings, and what the invention consists in will be more particularly defined in the appended claims.

In the drawings, wherein the same reference characters designate the same or similar parts in the several views, Figure 1 is a top view of a side frame embodying the invention; Fig. 2 is a side view and Fig. 3 is an end view of the same; Fig. 4 is a vertical cross-section on the line 4—4 in Fig. 2; Fig. 35 5 is a horizontal cross-section on the line 5—5 in Fig. 2; Fig. 6 is a plan view of a modified form of side frame embodying the invention; Fig. 7 is a side view of the side frame shown in Fig. 6; Fig. 8 is a vertical cross-section on the line 8—8 in Fig. 6; and Figs. 9, 10 and 11 are detail views of modified forms of brake hanger and wear clip for use with side frames embodying the invention, Fig. 9 being a side view, Fig. 10 40 being a vertical section on the line 10—10 in Fig. 9, and Fig. 11 being a top plan view thereof, respectively.

The side frames shown in the drawings consist of three principal members which 50 are riveted together, namely, a main longitudinal member having top and bottom portions, and constituting a one-piece tension chord and compression chord member, a

middle bolster or column member, and a top chord brace; and in addition thereto a lower 55 tie rod which is detachable. The pedestals for the journal boxes may be of any desired type, and they are bolted to the ends of the side frames and their lower ends are connected by the tie rods in any suitable 60 manner. These pedestals are not shown in the drawings.

Referring to Figs. 1 to 5, inclusive, the side frame shown therein consists of a forged or pressed steel principal truss member 11, which is substantially U or channel shape in cross-section at its ends and which is provided with a stiffener or channel 12 which extends nearly from end to end thereof and is riveted between the top edges of 65 its side walls. This channel shape brace member is arranged with its web horizontal and its side flanges extending upward and riveted to the upper edges of the side walls of the main frame member 11. The side 70 walls of the main frame member are split about midway of their height for about two-thirds of their middle length and the bottom portion 13 thereof is bent down away 75 from the top portion to form a large enough 80 opening to receive the ends of the spring plate and bolster and inclose the truck springs. The main frame member 11 may be constructed in any suitable manner but preferably is made in accordance with the 85 member described in my Patent No. 1,125,296, dated Jan. 19, 1915. The side edges of the downward extending portion 13 of the main frame member are twisted outwardly and downwardly, and the middle 90 length thereof is inverted channel shape in cross-section. The middle length of the portion 13 is provided with outwardly extending flanges 19 along the lower extremity of its side walls in order to stiffen this 95 portion of the frame against both vertical and lateral loads. A forged or pressed steel bolster frame member 14 connects the top and bottom portions of the main frame member and supports the spring plate 15 100 and wear plates 16 for the bolster. Brake hanger brackets 17 are also supported from the columns 14. A tie bar 18 is provided for connecting the lower ends of the journal boxes. The bolster frame member 14 is 105 made of pressed steel and is shaped like the

letter U in its general configuration. It is channel shape in cross-section and the side walls of the free ends of the side column portions 14 project through the web of the channel 12 and are riveted to the top portions of the frame member 11. The ends of the middle web portions of the columns are provided with horizontally extending flanges which are riveted to the under side of the web of the channel 12. The middle connecting portion of the bolster frame member 14, which is inverted channel shaped in cross section, is arranged astride of the lower middle portion 13 of the frame 11 and is riveted 10 to the side walls thereof. The spring plate rests directly on the middle portion of the bolster frame member and is riveted through its top wall and through the web of the bottom portion 13 of the frame. The 15 rivets which secure the spring plate 15 in place project through the middle web of the lower portion 13 of the frame 11 and form studs 20 which project into corresponding holes in the tie bar 18 for positioning it longitudinally of the lower portion of the 20 frame. The tie bar 18 is inverted channel shape throughout its middle length and fits within the space between the side walls of the depressed portion 13 of the frame member 11. The trussed shape of the side frame causes the top portion thereof, which is braced by the channel member 12, to be in compression from end to end, and causes the 25 depressed bottom portion 13 and the inclined portions which connect it with the ends of the main frame member to be in tension. The bolster frame or column member 14 is in compression at the columns, and its lower portion which is riveted to the depressed 30 portion 13 of the frame 11 is in tension. The effect of side thrust on the side frame may be to increase the tension stresses and to decrease the compression stresses on one side of the side frame, and vice versa on the 35 other side of the side frame. There may be a reversal of stress in the upper and lower horizontal portion of the side frame from tension to compression or from compression to tension under a sufficiently great side 40 thrust. The shape of the cross-section of the side frame through its upper and lower horizontal portions is that of a channel with horizontal webs and heavy vertical flanges and is especially adapted to withstand side 45 thrust.

In the modified form of side frame shown in Figs. 6, 7 and 8 the main frame 21 and bolster frame or column member 22 are similar to the main frame member 11 and bolster column member 14 of the side frame shown in Figs. 1 to 5. The top channel 23 of the side frame shown in Figs. 6, 7 and 8 is arranged with its horizontal web uppermost and its side flanges extending down between the sides of the top portion of the main

frame member 21 and riveted thereto throughout their length. This construction provides more vertical space between the columns for the bolster plates, springs and bolster.

In the construction shown in Figs. 9, 10 and 11 the brake hanger 24 is riveted to the horizontal web portion of the top channel 12 instead of being supported by the columns 14 as in the construction shown in Figs. 1 to 5. It is evident that the spring hangers may be secured in other ways than those illustrated, and that the shape and arrangement of the parts of the side frame afford ample room for attaching the brake 70 hangers where desired. Pressed steel wear plates 25 are shown in Figs. 9, 10 and 11, and it is evident that either cast, forged or pressed steel wear plates may be used with either form of side frame.

The invention is not restricted to the details of the construction and form and arrangement of the parts shown and described.

I claim the following as my invention:

1. A car truck side frame comprising a 90 main longitudinal frame member having its ends channel shaped, the side walls of said channel being separated along approximately horizontal lines throughout the middle portion of their length, and the bottom 95 portion of said channel being bent downward and twisted or turned inside out into inverted channel shape in cross-section, spaced vertical members connecting the bottom portion of said frame with the top portions thereof and inclosing a space for the bolster and springs, and a longitudinal brace member connecting said top portions between their ends and the tops of the vertical members, said members being rigidly 100 secured together and constituting a truss for supporting vertical loads and a webbed girder for resisting horizontal thrusts.

2. A car truck side frame comprising a 110 main longitudinal frame member having its ends channel shaped, the side walls of said channel being separated along approximately horizontal lines throughout the middle portion of their length, the top portions 115 thereof being spaced apart and the bottom portion being bent downward and twisted outward and downward into inverted channel shape in cross-section, spaced vertical members connecting the bottom portion of said frame with the top portions thereof and inclosing a space for the bolster and 120 springs, and a longitudinal brace member connecting said top portions throughout their length, said members being rigidly secured together and constituting a truss for 125 supporting vertical loads and a webbed girder for resisting horizontal thrusts.

3. A car truck side frame comprising a 130 main longitudinal frame member having its ends channel shaped, the side walls of said

- channel being separated along approximately horizontal lines throughout the middle portion of their length, and the bottom portion thereof being spaced below the top portions and of inverted channel shape in cross-section, said bottom portion having outwardly extending flanges along the lower edges of its side walls, spaced vertical members connecting the bottom portion of said frame with the top portions thereof and inclosing a space for the bolster and springs, and a longitudinal brace member connecting said top portions, said members being rigidly secured together. 5
4. A car truck side frame comprising a main longitudinal frame member having its ends channel shaped, the side walls of said channel being separated along approximately horizontal lines throughout the middle portion of their length, and the bottom portion thereof being spaced below the top portions and of inverted channel shape in cross-section, spaced vertical members connecting the bottom portion of said frame 10 with the top portions thereof and inclosing a space for the bolster and springs, said vertical members being connected at their bottom ends by an inverted channel shape member which is fitted over and incloses the side walls of said bottom portion, and a longitudinal brace member connecting said top portions, said members being rigidly secured together. 15
5. A car truck side frame comprising a main longitudinal frame member having its ends channel shaped, the side walls of said channel being separated along approximately horizontal lines throughout the middle portion of their length, and the bottom portion thereof being bent downward with its edges twisted downward and outward at the middle into an inverted channel shape, spaced vertical members connecting the bottom portion of said frame with the top portions thereof and inclosing a space for the bolster and springs, and a longitudinal brace member connecting said top portions between their ends and the tops of the vertical members, said members being rigidly secured together, and a tie rod arranged below said truss for connecting the journal box pedestals, said tie rod being removably secured between the side walls of said bottom portion. 20
6. In combination, in a car truck side frame or the like, a main frame member comprising two laterally spaced compression members and a tension member, said members being integral at their ends and bent away from each other vertically at their middles, a horizontal brace member spaced above said tension member and secured between the ends of said compression members lengthwise thereof whereby the ends of said frame are box shape, and a middle frame member secured upon said tension member at its middle and having upwardly projecting ends forming columns secured at their extremities to said spaced compression members. 25
7. In combination, in a car truck side frame or the like, a main frame member comprising two laterally spaced vertically disposed compression members and a horizontally disposed tension member, said members being integral at their ends and bent away from each other vertically at their middles, a horizontal brace member secured between said compression members and spaced above said tension member from end to end thereof whereby the ends of said frame are box shape, and a middle frame member secured longitudinally upon said tension member at its middle and having upwardly projecting ends forming columns 30 secured to said longitudinal brace member. 70
8. In combination, in a car truck side frame or the like, a main frame member comprising two laterally spaced compression members and a tension member, said members being integral at their ends and bent away from each other vertically at their middles, a horizontal brace member spaced above said tension member throughout its length and secured between the ends of said compression members along their upper edges lengthwise thereof, whereby the ends of said frame are box shape and a pair of spaced columns secured at their lower ends to said tension member near its middle and having upwardly projecting ends forming columns secured at their upper extremities to said spaced compression members. 35
9. A car truck side frame having a main frame member or truss comprising three principal parts made of forged, rolled or pressed steel, said parts being a longitudinal channel shape member having its side walls vertical and split lengthwise and spread apart vertically throughout their middle length, the lower portion constituting a tension chord; a top web rigidly secured between the top portions of said side walls lengthwise thereof and forming therewith a combined compression chord and horizontal girder; and a middle bolster frame rigidly secured to said compression chord and tension chord at top and bottom respectively. 40
10. A car truck side frame having a main frame member or truss comprising three principal parts made of forged, rolled or pressed steel, said parts being a longitudinal channel shape member having its side walls vertical and split lengthwise and spread apart vertically throughout their middle length, the lower portion constituting a tension chord; a top web rigidly secured between the top portions of said side walls lengthwise thereof and forming therewith a combined compression chord and 45

horizontal girder; and a middle bolster frame rigidly secured to said compression chord and tension chord at top and bottom respectively, said bolster frame carrying a horizontal spring plate, and a tie rod detachably secured below said main frame member.

Signed at Pittsburgh, Pa., this 30th day of June, 1915.
